UNITED STATES PATENT OFFICE.

ELBERT STALLWORTH, OF AMERICUS, GEORGIA.

ELECTRIC HEATER.

Application filed December 19, 1927. Serial No. 241,104.

The invention relates to improvements in electric heaters by means of electric heating wire extending around a porcelain tube enclosed by a concave reflector which is attached 5 within the walls of the heater; and by a humidifier located above reflector under top of heater; and the objects of the improvements are, first, to cause air passing upward through the vacuum of the reflector to become 10 hot by radiant heat produced by heating wire connected with electric current; second, to conserve the heat radiated by the polished concave walls of the reflector which cause the heat by reflection to converge to a focus in the 15 direct path of the air, said reflection augmenting the radiant heat from heating wire; third, to cause hot air from the vacuum of the reflector to become humidified by vapor from water in a receptacle located in hot 20 air passage under top of heater.

One form of the invention is illustrated in the accompanying drawing, in which Figure 1 is a general view of heater, indicating air outlet through top. Fig. 2 is an interior view 25 of heater, showing location of heating element, concave reflector with perforated cold air inlet and location of the humidifier under top of heater. Fig. 2 also indicates the manner said parts are attached. Fig. 3 shows 30 an end view of humidifier and its position under top of heater. Fig. 4 is a detail view of heating element, showing the position of the porcelain tube in the socket of the terminal block, the arrangement of the heating wire 35 and the manner the heating element is attached to reflector.

Figure 1 illustrates hot air outlet 2 in heater top 1; the position of water tube 3 by which water is put in the humidifier; the humidifier 40 water gauge 4; and the manner in which the heater is held together with flat head bolts 5. The lower edges of heater are bordered with narrow piece 7, said border soldered to edges. In Fig. 2, bolts 5 extend through top 45 of heater, through rectangular reflector support 14, through edge 15 of heater to nut soldered under said edge 15. Heating element 10 is screwed to reflector 6. The reflector is supported by being bolted to rectangu-

lar support 14. Reflector support 14 has air 50 passage at top of reflector same size as opening 18. Humidifier 16 is held in place under top of heater on one end by water tube 3 which is soldered to top of heater and said humidifier, also by water gauge tube 4 which is attached in same manner. At the other end the humidifier is soldered to strip 17 which is attached in same manner to side of top. The humidifier has, as indicated, perforated outlet for vapor. In filling humidifier, 55 water is poured through tube 3 until it appears in gauge tube 4, which indicates the level of the water in humidifier. In Figure 3, the humidifier is shown with one side beveled in order that it may fit closely against 60 beveled side of top. The short beveled portion of humidifier near top contains the perforated outlet for vapor. In Figure 4, heating wire extends from terminal through porcelain tube 10, passing through small holes 65 at top of tube and in spiral manner around tube to base of same, said heating wire 13 extends through hole in base and terminal block to terminal as indicated. Porcelain tube 10 with base and small cylindrical end 70 fits into socket of terminal block in manner illustrated in Fig. 4. Two small screws extending through terminal block cover 9 into terminal block, hold said cover in place. A portion of inside wall of cover 9 near its 75 edge is threaded in order that said cover with terminal block and complete heating element 75 may be attached to reflector 6, screwed on lower portion of reflector at 8.

I claim:

In an electric heater, a casing, a spherical heating chamber suspended from the top of said casing, a heating unit extending vertically into said heater chamber thru a hole in the lowest portion thereof, perforations in 90 the bottom of said heating chamber about said heating unit, a circular air passage thru the upper portion of said heating chamber, a perforated top for said casing and a water receptacle supported under said perforated top to moisten the hot air which passes thru said perforated top.

ELBERT STALLWORTH.
